PAWL OPERATING MECHANISM

Garred T. Harris, Charleston, W. Va.

Application July 30, 1937, Serial No. 156,590

8 Claims. (Cl. 197—65)

This invention relates generally to pawl and ratchet mechanisms and more particularly to means adapted to be interposed between the pawl and pawl driving mechanism whereby motion of a predetermined character may be transmitted to the pawl.

Although the invention is of general utility and application wherever it is desired to control the movement of a pawl and move the same at a predetermined uniform or variable velocity, the invention has particular utility in connection with pawl and ratchet mechanism where the shaft or other element to which the ratchet wheel is attached has a tendency to overrun due to the impetus imparted thereto during the driving stroke of the pawl. Thus, in conventional typewriter machines where the platen is intermittently rotated by means of a pawl and ratchet mechanism operated through a manually controlled lever, the platen is often rotated so rapidly and so suddenly that in instances where multiple copies are being typed, there is a marked tendency for the several sheets engaging the platen to relatively shift and thus bring the typed matter out of alignment.

In present day typewriting machines it is common practice to provide a hand-operated lever mounted on the carriage and by operation of which the carriage may be returned or back-spaced as well as the platen partially rotated to line space.

Usually the lever is arranged so that it is given an initial rocking or pivotal movement to effect line spacing and continued application of pressure upon the lever effects back-spacing or carriage return. It has been found that these mechanisms possess an inherent characteristic which is objectionable in that it leads to defective operation when the machine is being rapidly operated by an experienced and fast operator. This objection arises due to the fact that the operator will give the lever a sharp, heavy blow sufficient to rapidly overcome the inertia of the relatively heavy carriage mechanism, and such blow, when communicated to the line spacing mechanism by the initial movement of said lever, causes relative slipping of the work in the machine, particularly in cases where multiple carbons are being made. This slipping has been diagnosed by persons skilled in the art to be the result of the heavy, sharp blow delivered to the line spacing lever by the operator in returning the carriage from left to right, in that it rotates the platen in line spacing so quickly as to cause relative slipping of papers in the machine due to the inertia thereof.

with respect to the driving force of the platen.

Furthermore, it is well known among experienced typewriter operators that the continual shifting of the carriage by the hand operated lever usually provided on such machines, is an exceedingly strenuous task when typing continuously throughout relatively long periods of time such as six to eight hours a day, as is common in general office practice.

With these facts in mind the invention seeks to provide means for relieving the operator of the necessity of taking her hand from the keyboard to shift the carriage from left to right and for line spacing and to transfer this burden from the hand of the operator to the foot. Thus the operator is enabled to work more efficiently by having both hands on the keyboard at all times.

Another object of the invention is to provide a line spacing mechanism including a pawl and ratchet drive for the platen, which will preclude the possibility of slippage between papers in the machine due to operation of the line space lever as above noted.

Another object of the invention is to provide means for slowing down the motion of the line space lever to a degree sufficient to prevent relative slipping of the papers in the machine due to inertia when the platen is rotated to line space.

Another object of the invention is to provide in an apparatus of the character indicated, means for adjusting the power transmission mechanism to the foot of the operator, and to detachably connect the same to the table or desk on which the typewriting machine is supported, by relatively simple and inexpensive mechanism.

Another object of the invention is to provide in a treadle-operated cable transmission mechanism of the character described, a combined bracket and pulley unit which may be secured to a support by a single hollow bolt member which functions concurrently as a cable guide for the cable of the transmission mechanism.

Another object of the invention is to provide motion transmission means adapted to be interposed between the pawl of a pawl and ratchet mechanism and the pawl driving mechanism for the purpose of transmitting to the pawl motion of predetermined character.

These and other objects of the invention will become apparent by a reading of the following specification taken in connection with the accompanying drawings, wherein I have illustrated a preferred form of my invention, but it is to be understood that various changes in details and combinations of parts as disclosed may be made.

without departing from the spirit of the invention as set forth more particularly in the appended claims.

In the accompanying drawings:

- 5 Figure 1 is a perspective view, partly in section, of a typewriting machine having associated therewith the mechanism forming the subject-matter of the present invention.
- 10 Fig. 2 is a plan view of the foot-operated treadle.
- 15 Fig. 3 is a side elevation of the treadle.
- Fig. 4 is a vertical sectional view showing the pulley and supporting bracket therefor.
- 20 Fig. 5 is an elevation partly in section of the pulley bracket.
- 25 Fig. 6 is a detail view of the motion slow-down lever in its fully retracted position.
- Fig. 7 is a perspective view of a slow-down lever and link for attachment to a slightly different form of typewriter from that shown in Fig. 1.
- 30 Fig. 8 is a further modified form of slow-down lever and link for a still different form of typewriter.
- 35 Fig. 9 is a diagrammatic view illustrating the broader aspects of my invention as applied to a simple pawl and ratchet mechanism.
- 40 Fig. 10 is a diagrammatic view showing my invention applied to a pawl and ratchet mechanism of the character wherein means are provided for adjusting the effective stroke of the pawl for moving the ratchet a greater or lesser amount, as desired.
- 45 Fig. 11 is a diagrammatic view similar to that shown in Fig. 10 but slightly modified as to detail.
- 50 Referring more particularly to the accompanying drawings wherein like reference numerals are used to designate like parts throughout, I have shown in Fig. 9 a ratchet wheel 75 mounted upon a shaft 76 in a manner such that rotation of the ratchet wheel 75 will cause rotation of the shaft 76. The shaft 76 may be connected to any mechanism to be operated, such as the platen of a typewriting machine. A pawl 77 is pivotally mounted on the pawl arm 78 and said arm is pivotally supported at a convenient point such as upon the shaft 76, as shown. The pawl 77 is maintained in operative contact with the teeth of the ratchet wheel 75 by means of a suitable spring 79. The pawl and pawl arm are biased to a predetermined retracted position by means of the spring 80 connected between the pawl arm 78 and a pin 81. Cooperating with the spring 80 is an abutment 82 positioned to define the normal or retracted position of the pawl. Any convenient means may be arranged to drive the pawl. In the present instance I have indicated a cable 83 which may be connected to any suitable source of power, such as a treadle mechanism as shown in Figs. 1 and 3. Interposed between the cable 83 and the pawl arm 78 I provide mechanism for determining the character of motion to be transmitted to the pawl arm 78. This mechanism in the present embodiment of my invention, comprises a cam plate 84 pivotally mounted at 85 on a suitable bracket or support 86, and having an arcuate cam edge 87. The cam plate 84 is maintained in a normal retracted position against a stop member 88 by a retractile spring 89 having one end attached to the abutment 82 and the opposite end attached to a lug 90 carried by the cam plate 84, adjacent the pivot 85 thereof. Thus, due to the disposition of the lug 90 and the stop abutment 88 with reference to the pivot 85, the spring 89 tends to maintain the cam plate 84 in the position shown in Fig. 9. The bracket 86

extends beyond the cam plate 84 to provide a pivotal mounting 91 for a bell crank lever generally indicated at 92. One arm 93 of the bell crank overlies the cam plate 84 and has the free end 94 pivotally connected to a link member 95, the opposite end of which is pivotally connected to the pawl arm 78 at the point 96. The other arm 97 of the bell crank lever 92 is provided with a roller 98 arranged to bear against the cam edge 87 under the influence of the retractile spring 80 hereinbefore referred to. Thus, it will be seen that an intermittent pulling force applied to the cable 83 operates to rock the cam plate 84 about its pivot 85 against the tension of the return spring 89. The cam plate has the contour of the cam edge 87 designed to impart to the bell crank 92 through the roller 98 motion of a predetermined character which is transmitted through the bell crank and link 95 to the pawl and pawl arm 77, 78. It is apparent that this arrangement provides definite means for delivering to the pawl arm 78 motion of adjustable or variable velocity throughout a substantially infinite range of adjustment.

The mechanism shown in Fig. 9 is designed to give the same extent of movement to the ratchet wheel 75 and associated shaft 76 for each operation of the pawl; that is, regardless of the character of the motion transmitted to the pawl, the pawl is effective for one operative stroke to move the ratchet and associated shaft a given amount. In Fig. 10 I have shown a modified form of pawl and ratchet mechanism embodying my invention wherein means are provided for adjusting the throw of the pawl throughout a range of one, two or three ratchet teeth. One form of adjustment comprises a pawl restraining cam plate 99 pivotally mounted upon a shaft 76 and having a cam portion 100 disposed substantially parallel to the axis of shaft 76 and interposed between the teeth of the ratchet wheel 75 and the pawl 77. Thus, the pawl biasing spring 79 tends to maintain the nose of the pawl in contact with the hold-out cam 100. It will be noted that the cam 100 has an arcuate or angular extent substantially equal to the width of two ratchet teeth. Thus, in the position shown in Fig. 10 with the nose of the pawl 77 resting adjacent the left hand edge of said cam portion, the pawl in its first increment of movement under the driving impulse of the cable 83, drops into operative engagement with the ratchet tooth 101 to move the ratchet wheel 75 throughout the entire range of driving movement of the pawl arm 78, which in the present instance is the space of three ratchet teeth, as indicated by the numeral 3 on the indicia plate 102 with which a suitable pointer 103 carried by the cam plate 99 cooperates. If the cam plate be shifted in a counterclockwise direction to bring the pointer 103 into alignment with the numeral 2 on the indicia plate 102, the nose of the pawl 77 will lie substantially midway between the ends of the cam portion 100 with the pawl in the retracted position shown in Fig. 10. Thus, for an operating impulse on the cable 83 the pawl 77 will, for the first increment of its driving movement, ride upon the surface of said cam portion 100, during which movement it is ineffective to drive the ratchet wheel 75. The parts of the mechanism are designed so that this increment of pawl movement is substantially equivalent to the space of one ratchet tooth so that when the pawl drops into operative engagement with the teeth of the ratchet there remains an increment of driving movement substantially 75

equal to two ratchet teeth, so that in this setting of the apparatus the ratchet wheel 75 is driven two spaces. Similarly, if the cam plate 99 is moved to bring the pointer 103 in alignment 5 with the numeral 1 on the indicia plate 102, the pawl 77 is maintained ineffective for the space of two ratchet teeth so that it delivers a driving impulse to the ratchet wheel 75 equivalent to substantially one ratchet tooth only.

10 In the arrangement just described it is apparent that so long as the pointer 103 is in the position shown, full advantage of the contour of cam plate 84 may be realized in controlling or modifying the movement of pawl 77 and pawl arm 78.

15 However, when the pointer 103 is shifted to either No. 1 or No. 2 positions as indicated by the scale 102, the pawl 77 must ride a greater or lesser extent upon the surface of the cam 100 before dropping into operative engagement with 20 the teeth of the ratchet 75. This is objectionable in some instances in that full benefit of the cam contour is not realized. This feature, however, is remedied by the provision of a plurality of apertures in the arm 93 of the bell crank lever 92 by which the link 95 may be connected to said arm in a plurality of positions. These apertures are indicated in Fig. 10 by the reference numerals 25 104^a, 104^b and 104^c. The respective locations of these apertures on the lever arm 93 are obtained in the following manner: With the pawl arm 78 in its fully retracted position against the abutment 82, and with the cam plate 84 and bell 30 crank lever 92 in their normal or fully retracted position, an arc is struck about the pivot point 96 on the pawl arm 78 through the center of the bell crank pivot 91. The cam plate 94 is now moved substantially 90° into the dotted line position shown in Fig. 10 and with the bell crank 92 in its fully displaced position, also indicated in 35 dotted lines, an arc intersecting the first drawn arc is struck from the pivot point 96 upon the lever 78 with said lever moved counterclockwise a distance such as to move the ratchet wheel 75 a distance corresponding to three full teeth, or 40 such as shown in dotted lines in Fig. 10. The point of intersection between these two arcs determines the location of the aperture 104^a. The apertures 104^b and 104^c are similarly located by striking arcs intersecting the first drawn arc 45 from the pivot point 96 with the pawl arm 78 successively moved counterclockwise a distance corresponding to movement of the ratchet 75 a distance of two teeth and one tooth, respectively.

50 It is to be noted in this connection that the cam plate 94 has an effective arcuate extent comparable with the roller 98 of the bell crank 92 of substantially 90°. The contour of the cam is designed so that the first increment of angular 55 or pivotal movement of the plate 84 is utilized for moving the pawl 77 from its retracted position on the hold-out cam surface 100 to a position operatively engaging the ratchet tooth 101 and the remainder of the contour of cam plate 84 is fashioned and utilized for the purpose of modifying and controlling the effective movement of the pawl. It will be realized that by determining the location of the connecting apertures 104^a, 104^b, 104^c in the manner described, the movement 60 of the pawl effective to move the ratchet 75 one, two or three tooth spaces, may be readily accomplished by connecting the link 95 to the lever 93 in the desired aperture. By having all of the apertures 104^a, 104^b and 104^c located on an arc 65 about the pivot 96 with the pawl in its fully re-

tracted position, said pawl may assume such position in all arrangements of connection between the link 95 and the lever 93. Similarly, it will be appreciated that by determining the position of the apertures 104^a, 104^b and 104^c on the arc just mentioned, the movement communicated to the pawl by the cam plate 84 will be effective to move the ratchet 75 a space of one, two or three teeth depending upon the connection of the link 95 in apertures 104^c, 104^b and 104^a, respectively. 10 It is also to be noted that in the arrangement just described the same major portion of the contour of cam plate 84 is utilized for moving the pawl 77 irrespective of the point of connection between the link 95 and the lever arm 93. This 15 feature provides means for definitely controlling or modifying the motion communicated to the pawl in all positions of adjustment of the link 95.

I have shown in Fig. 11 a further modification of my invention by which substantially the full 20 contour of the cam 84 may be utilized for controlling or modifying the movement of the pawl. Generally speaking, this modification differs from that shown in Fig. 10 in that the effective movement of the pawl is terminated at the same point 25 for all positions of adjustment of the link 95, whereas in the modification shown in Fig. 10 the arrangement is such that the pawl starts from the same point in all positions of adjustment of the link 95 but terminates at different 30 positions depending upon the degree of operative throw of the pawl desired.

Referring more particularly to Fig. 11, I provide an abutment 182 adjacent the periphery of the ratchet wheel 115 and in the path of movement of the pawl 177. The pawl 177 and the abutment 182 are designed to cooperate to terminate the effective movement of the pawl and to this end I provide the pawl 177 with a flattened nose portion 177^a. This arrangement necessitates a slightly different disposition of connecting apertures on the arm 193 for the link 195. Thus the cam plate 84 is moved substantially 90 degrees from the position shown in full lines in Fig. 11 to the position shown in dotted lines in 45 such figure and with the bell crank 192 displaced correspondingly due to the engagement of the roller 198 with the contour of the cam 84, an arc is struck through the center of the pivot 191 from the point 196 on the pawl arm 178 when 50 said arm is in the position such that the nose 177^a of the pawl 177 is in engagement with the abutment 182. The arc so drawn will determine the general location of the points of connection for the lever 195 on the arm 193 to terminate the effective movement of the pawl at the abutment 182. To determine the actual point of location on the arm of the apertures by which the link is connected thereto, the pawl arm 178 is moved from the dotted line position in which 55 the pawl is in engagement with the abutment 182 clockwise distances corresponding respectively to one, two and three ratchet teeth, and from these positions intersecting arcs are struck about corresponding positions of the point 196 60 through the first struck arc with the lever 192 and the cam plate 194 in a position displaced substantially 30 degrees from that shown in full lines in Fig. 11. The 30 degrees mentioned is purely arbitrary and can be increased or diminished according to the requirements of a given application, it being noted that this initial increment of movement of the cam plate 84 is utilized for moving the pawl 177 from its position 65 of engagement with the hold-out cam 200 into 70 75

operative engagement with the first ratchet tooth 201. It will also be understood that in this modification of my invention it is necessary to shift the hold-out cam 200 to bring the pointer 203 into alignment with the proper indicia on the plate 102 for each position of adjustment of the link 195 on the arm 193, since the points of connection on said lever arm 193 are located in a manner such as to draw the pawl arm 178 in a 10 counterclockwise direction as the eccentricity of the point of connection is reduced.

The connection between the link 95 and arm 93 and between the link 195 and the arm 193 may be any desired type of quick-detachable connection which will facilitate shifting the point of connection of the link to the desired aperture in the lever arm.

In both forms of my invention shown in Figs. 10 and 11 it will be noted that I arbitrarily utilize a small angular extent of the contour of the cam plates 84 for moving the pawl from its inoperative position in engagement with the hold-out cam into operative engagement with the first ratchet tooth. Also, this initial increment of cam contour is designed to have but a slight degree of eccentricity with respect to the pivot of the cam plate so that the pawl is slowly moved into engagement with the first ratchet tooth. This avoids all possibility of shock due to impact between the pawl and ratchet tooth and thereby avoids the possibility of slippage between the shaft 76 and any means or element which is frictionally driven therefrom, such as the papers in a typewriting machine where the shaft 76 carries the platen of such machine.

It is also to be noted in connection with the form of my invention shown in Fig. 10 that, due to the variable eccentricity of the points of connection between the link 95 and the lever 93, there will be a slight variation in the actual point of contact between the roller 98 and the cam plate 84 when the pawl 177 actually engages the ratchet tooth 101. This variation is, however, so slight as to be entirely negligible in the 40 operation of the invention as described. Similarly, in the modification shown in Fig. 11, the variable eccentricity of the point of connection between the link 195 and the lever arm 193 will affect the actual point of contact between the 45 pawl 177 and hold-out cam surface 200 in the normal or retracted position of the pawl for the different adjustments of the link 195. Here again, however, the variation is so slight as to be entirely negligible in controlling or modifying 50 the movement of the pawl.

Referring now to Fig. 1, I have shown my invention applied to a well known form of typewriter in wide use today, and which employs a combined line space and carriage return lever 60 indicated generally by the reference character 1. The lever 1 is pivoted at 2 to a portion of the typewriter carriage mechanism 3 and is connected by link 4 to the platen rotating pawl and ratchet mechanism 5-5a. Thus, in operation, 65 the operator by striking the outer end of the lever 1, rocks the same about its pivot 2 to actuate the pawl mechanism 5 to partially rotate the platen to effect a line spacing operation and, as the portion 6 of said lever engages the stop member 7 carried by the carriage, its rotational movement is arrested and further application of 70 force to said lever causes return movement of the carriage from left to right. In the usual operation of the machine the operator strikes 75 the free end of the lever 1 a forceful blow at the

end of each line of typing to successively line space for a new line and return the carriage to the right hand side of the machine to effect alignment of the point of type bar impact with the margin of the work. As hereinbefore indicated, this operation on the part of the operator when continued over long periods of typing, is extremely enervating, and due to the inherent characteristics of such mechanism, results in relative slipping of sheets of work in the machine 10 due to the rapidity with which the platen is rotated when struck by the operator in the normal course of return of the carriage from left to right. It is understood that the mechanism thus far referred to is an integral part of the typewriter machines as purchased and forms no part of the present invention.

My invention may readily be designed as an attachment for machines of the type hereinbefore referred to, and which will relieve the operator of the necessity of line spacing and returning the carriage to the right by hand, and includes an attachment which may be readily mounted on the machine and not affect the otherwise normal operation thereof. Thus, my 20 invention contemplates a bracket member 8 which may be secured to the carriage of the machine in any suitable manner. In the form of machine shown in Fig. 1 the bracket may conveniently be secured to the rear left side of the 25 machine as viewed from the operator's position, by means of a screw and nut provided on the machine to secure parts thereof together. Thus the nut 9 normally employed for securing the end of the rod 10 to the end of the carriage, may 30 be removed and likewise the screw or bolt 11 also employed for securing the part of the machine to the carriage and plate is removed, and the bracket 8 having a suitably apertured 35 upstanding wing portion 12, is then fitted over the 40 projecting end of the rod 10 with an aperture in alignment with the hole in the carriage end plate for the bolt 11, after which the bolt 11 and the nut 9 are replaced in their proper position and the bracket 8 is thus securely fastened to the end 45 plate of the carriage without the necessity of supplying any additional parts.

The bracket 8 comprises an outstanding, substantially horizontal portion 13 upon which is mounted at point 85, the cam plate 84 previously referred to in Figs. 9, 10 and 11. The bell crank lever 92 is pivotally mounted on a portion of the plate 13 projecting beyond the cam plate 84, with the roller 98 carried at the free end of the arm 97 of said lever bearing against the cam 55 edge 87 of the plate 84. The opposite arm 93 of the bell crank 92 is provided with the spaced apertures 104 for connection with the link 95, as shown, the opposite end of said link being connected to the pivotal connection 18 between the 60 lever 1 and the pawl driving link 4. By this arrangement it is apparent that the pivotal movement of the plate 84 is communicated to the bell crank 92 through the cam edge 87 and as modified thereby, is delivered to the pawl 65 mechanism 5, 5a in the manner hereinbefore described in connection with the modifications shown in Figs. 9, 10 and 11.

While I may employ either the modification shown in Fig. 10 or 11, I prefer, for use in typewriter mechanism, to employ that shown in Fig. 11, since it definitely precludes any variation in spacing of the platen due to wear of the pivot links, etc., inasmuch as the effective movement of the pawl transmitted to the ratchet is defi- 75

nately predetermined by the abutment 182 of Fig. 11.

My invention contemplates actuation of the cam plate 84 by means of a foot operated instrumentality such as a foot treadle shown at 19 in Fig. 1. The foot treadle may have any convenient form but preferably comprises a suitable frame member 20 provided with a generally upstanding peripheral flange 23 within which is adjustably and pivotally mounted the treadle 19. The treadle 19 adjacent the end nearest the operator is provided with spaced wing portions 24 as shown in Fig. 3, said portions depending from the foot portion of the treadle. The wing portions 24 are provided with one or more apertures 25 to receive a fulcrum pin 26, the latter passing through the upstanding flanges 23 of the frame member and through aligned apertures 25 in the wing portions 24 of the treadle. By this arrangement the treadle member is pivotally mounted in the frame member 20 and may be readily adjustable fore and aft with respect to the frame and pivot member 26 for the purpose of properly balancing and proportioning the pedal to the size of the operator's foot and the normal range of pivotal movement thereof provided at the ankle joint. At the toe portion of the treadle 19 I provide an overhanging bracket member 27 having an end portion 28 disposed above the toe portion of the lever 19 and provided with a plurality of apertures 29 by which a cable member 30 may be adjustably secured thereto. It will be understood that the cable 30 may be secured to the bracket 27 in any one of the apertures 29 and thus provide means for properly proportioning the lever action of the treadle 19 to the strength of the operator.

The cable 30 passes upwardly from the bracket 27 through a hollow bolt and guide member 31 by which a pulley supporting bracket 32 is secured to the top of the desk or table 22. As shown in Figs. 4 and 5, the pulley and bracket assembly includes the bracket member 32 which is formed with a substantially horizontal foot portion 33 and an upstanding bracket portion 34. The foot portion 33 is apertured for alignment with an aperture in the table top 22 so that the bracket member 32 may be conveniently secured to the table top by means of the hollow bolt member 31, the latter serving simultaneously as a guide for the cable 30 and as means for securing the bracket to the table. Projecting laterally from the bracket portion 34 of the bracket and pulley assembly is a stub shaft 35 upon which a double pulley comprising a large pulley 36 and a small pulley 37 is mounted. The cable 30, one end of which is attached to the bracket 27 of the treadle, has its opposite end wound about the small pulley and secured thereto as at 38. The large pulley 36 has wound thereabout a second cable 30', the end of which is secured to the pulley as at 39. The dual pulley unit 36, 37 is housed within a suitable casing 40 which is secured to the bracket member 34 by means of a plate member 41 which is engaged over the threaded end 42 of the stub shaft 35 and secured thereto by any suitable means such as the nut 43. As shown in Fig. 4, the casing member 40 is suitably apertured as at 44 and 45 to permit free passage of the cables 30 and 30', respectively, therethrough.

It is further to be noted that the frame member 20 which supports the foot treadle 19 is arranged to be adjustably secured to the legs 21 of the bench or table 22 upon which the typewriting machine is mounted. Thus, the frame 20

as shown in Figs. 1 and 2 is provided with suitable strap members 10 secured to said frame and extending in divergent relation therefrom. The strap members 10 are provided at their free extremities with fastening elements 11 designed to be wrapped about the lower portion of the legs 21 and thus secure the frame in fixed position thereto. The straps 10 being thus securely tied to the legs 21 prevent shifting or lateral movement of the frame member 20 during operation of the pedal 19 by the foot of the operator. Due to the manner of securing the straps 10 to the frame 20, said straps may be adjusted angularly with respect thereto in order to accommodate the apparatus to tables in which the legs are a greater or lesser distance apart. Reference is here made to the single securing element 12 by which the straps are secured to the lower flange of the frame 20. It is also to be noted that by the provision of a plurality of apertures in the horizontal plane of the frame 20 for said securing elements 12, the entire pedal unit may be shifted fore and aft to a proper position of adjustment for any operator.

Referring to Fig. 1, the pulley and bracket assembly 32 is shown provided with an upstanding pulley supporting arm 46 at the upper end of which is pivotally mounted a guide pulley 47. The cable 30' is led from the pulley casing 40 through the aperture 44 and is thence trained around the pulley 47 and carried transversely across the back of the typewriting machine and attached to a laterally projecting arm 48 provided on the plate 84.

The upstanding portion 12 of the bracket 8 is designed to cooperate with the flattened abutment portion 50 of the cam plate 84 to limit the extent of pivotal movement of said cam plate through an arc of substantially 90 degrees, as shown more clearly in Fig. 6. It will be understood that when the parts have reached the position shown in Fig. 6 continued pull on the cable 30' is effective to move the carriage from left to right. In order to relieve the bracket securing means 9 and 11 and the upstanding portion 12 of the bracket from undue strain during this shifting movement of the carriage, the horizontal portion 13 of the bracket is extended transversely of the carriage and embraces the eccentric stop pin 1, as clearly shown in Fig. 1.

In conventional typewriting machines of the type disclosed in Fig. 1 there are provided spring biasing means for maintaining the pawl mechanism 5 and the associated operating lever 1 in a normal retracted position. This spring mechanism (not shown) is sufficient to maintain the roller 98 of the bell crank lever 92 in operative engagement with the cam edge 87 of the plate 84. The plate 84 is biased to the position shown in Fig. 1 by the spring means 89 previously described in connection with Figs. 9 and 10 and in the arrangement shown in Fig. 1 this spring is also instrumental in elevating the treadle 19 when pressure thereon is removed. Obviously the spring 89 may be supplemented by additional spring biasing means associated with either the treadle 19 or the pulley unit 32.

In operation, the operator, when the carriage has reached the extreme left hand position of the machine as a result of having completed a line of typing, depresses the treadle 19 as a result of which the cam plate 84 is initially moved on its pivot 85 into engagement with the stop member 50. This operation actuates the pawl driving mechanism 4, 5 to advance the platen for effecting line spacing, and continued application

of force on the pedal 19 operates through the cables 30 and 30', cam plate 84 and stop member 50, to move the entire carriage mechanism to the right hand side of the machine. Upon release of pressure on the treadle 19 by the foot of the operator, the spring instrumentality associated with the lever 1, will retract the pawl driving mechanism 4, 5 to its normal position and through the instrumentality of the link 75, 10 the lever 92 is simultaneously retracted. The treadle 19 and plate 84 will be returned to normal position by spring 89. Due to the various adjustments provided in the motion transmission mechanism between the treadle 19 and the pawl driving mechanism 4, 5, the treadle 19 may be selectively operated to give line spacing without back spacing or successive line spacing and back spacing. Furthermore, due to the motion modifying cam plate 84 included in the power transmission mechanism just referred to, it is possible 15 to line space with the platen braking detent mechanism in inoperative position, and without any overrun or overthrow of the platen. The detent mechanism here referred to is that normally provided on machines of the type and through the instrumentality of which the rotary movement of the platen is checked or braked, and on the present machine is controlled by the lever indicated at 51. This provision 20 of means for line spacing accurately with the controlling detent mechanism in inoperative position further relieves the operator of a burden in that the drag of the platen due to the line spacing detent may be entirely dispensed with 25 and the platen accurately driven.

The line spacing adjustment mechanism provided in machines of the type illustrated in Fig. 1 is shown at 103 and by properly positioning this lever in accordance with a calibrated scale, not shown, but similar to that shown at 40 102 in Fig. 10, the pawl and ratchet mechanism 5-5a may be controlled to insure the platen being moved one, two or three spaces, as desired.

In Figs. 7 and 8 I have shown simplified modifications of my invention by which the motion transmitted to the pawl and ratchet mechanism by the cable attached to the treadle mechanism may be modified to the extent that the motion of the treadle is appreciably slowed down, 50 thus insuring a minimum impact between the pawl and associated ratchet. Thus, in Fig. 7 an attaching bracket 52 has a depending portion 53 arranged to position the horizontal portion 54 of the bracket at a level below the attaching portion of the bracket. The horizontal portion 54 has pivotally connected thereto at the point 55, a lever 55 which is connected by means of a link 58 with the pawl and ratchet operating 60 means of a machine of slightly different form than that shown in Fig. 1. The operating cable may be attached to the lever 55 at the point 56. One or more apertures 57 may be provided for adjustably connecting the link 58 to the bracket 55.

In Fig. 8 a lever 60 is shown pivotally connected to a bracket 61 by the pivot screw 62. A link 63 is pivotally connected to the lever 60 at point 64, said lever being designed for connection to a pawl and ratchet mechanism of the type illustrated on the machine in Fig. 1. Thus, the free end 65 of the link is designed for connection to the pivot screw 18 of the machine of Fig. 1. A spring member 66 has its opposite ends 75 connected to the lever 63 and an arm 67 of the

lever 60 for the purpose of biasing the lever 60 to its normal position, such as shown in Fig. 8.

Both of the simplified forms of my invention as shown in Figs. 7 and 8 are characterized by a peculiar disposition of pivotal connections between the link and lever and between the lever and bracket. This connection is such that the initial movement of the link, by reason of rocking movement of the lever, is substantially parallel to the line of movement of the pawl, where- 10 as during the final increment of pivotal movement of the levers, the point of connection between the link and lever moves substantially transversely to the line of movement of the pawl so that during the latter stages of rocking move- 15 ments of the lever, substantially little motion is imparted to the pawl. This result obtains from the relative disposition of the point of connection between the link and lever with respect to the pivotal axis of the lever, these points 20 being so arranged that the point of connection between the link and lever moves behind the pivotal axis of the lever during the final stages of pivotal movement of said lever.

In conclusion, it is apparent in view of the foregoing description and illustration in the accompanying drawings, that I have provided motion transmission means adapted to be interposed between a pawl and the means for driving it, whereby motion of any desired character may 30 be imparted to said pawl. Furthermore, I have provided a foot treadle operated mechanism for effecting line spacing and carriage return operation for conventional typewriter machines and in a form such that the mechanism may be 35 readily attached to typewriters of conventional form with a minimum of time and without the necessity of drilling or otherwise modifying the conventional typewriter machine to accommodate it to the mechanism forming the subject- 40 matter of my invention. Furthermore, due to the various adjustments provided in the power transmission mechanism between the treadle and the platen driving pawl, it is possible to line space independently of back space or carriage 45 return operations. It is also possible to accurately line space with my improved mechanism with the platen braking detent mechanism in inoperative position. This relieves the operator of the weight of drag of this brake mechanism 50 and thereby lessens the labor entailed in operating the machine.

It is further to be noted that one form of the invention is characterized by a motion modifying cam plate, the contour of which may be 55 designed to impart any desired type of motion to the pawl, such as shown in Figs. 1, 6, 9 and 10, whereas another form of my invention is characterized by a link and lever mechanism for communicating motion of a foot pedal to 60 the pawl and ratchet mechanism which drives the platen, and in which the connection between the link and lever is such that in the normal position of the parts the point of connection lies laterally of an imaginary line passing through 65 the pivot of the slow-down lever and the pivot of the line spacing lever supplied with the machine, so that as the slow-down lever is rocked by operation of the foot pedal, said point of connection moves in the arc of a circle about the 70 pivot of said slow-down lever with the result that during the final increment of movement of said lever, said point of connection is moving substantially transverse to the general line of movement of the link with respect to the pawl 75

which drives the platen. This construction precludes the possibility of overrun of the platen as the result of being rotated too rapidly.

It is to be understood that the drawings accompanying my application are illustrative only and that various changes in size and proportion of parts may be made in the apparatus therein shown without departing from the spirit of my invention, the important and novel features of which are set forth more in detail in the following claims.

Having thus described my invention, what I claim as new is:

1. In a typewriting machine including a rotatable platen, pawl and ratchet mechanism for intermittently driving the platen to effect line spacing, a pivoted lever, operator operated means for operating said lever, and linkage connecting said lever and said pawl, the point of connection between the linkage and said lever being such that during the initial movement of said lever said point of connection moves substantially parallel to the line of movement of the pawl, and in the final stages of movement of said lever said point of connection moves in a direction substantially transverse to the line of movement of the pawl.
2. In a typewriting machine including a rotatable platen, a pawl for driving the platen and a lever for actuating the pawl, the combination with said lever of a second lever, means for pivotally mounting said second lever on said typewriting machine, a link connecting said levers, the point of connection between said link and said second lever being eccentrically disposed with respect to the pivotal axis of said second lever an amount substantially equal to the operative range of movement of the pawl, pivotally mounted actuating means for said second-mentioned lever, and means for limiting the pivotal movement of said actuating means to substantially ninety degrees.
3. In a typewriting machine including a rotatable platen, a pawl for driving the platen and a lever for actuating the pawl, the combination with said lever of a second lever, means for pivotally mounting said second lever on said typewriting machine, a link connecting said levers, the point of connection between said link and said second lever being eccentrically disposed with respect to the pivotal axis of said second lever an amount substantially equal to the operative range of movement of the pawl, pivotally mounted actuating means for said second-mentioned lever, means for limiting the pivotal movement of said actuating means to substantially ninety degrees, and means included in said typewriting machine for maintaining said pawl in retracted position and said second lever in a position such that the point of connection between said lever and link is disposed laterally of an imaginary line passing through the pivotal axes of said first and second levers, and means for moving said pivotally mounted actuating means about its pivot through substantially ninety degrees, whereby said point of connection between the link and said second lever moves to a point substantially within said imaginary line.
4. An attachment for typewriting machines including a carriage, a rotatable platen carried by the carriage, a pawl for driving the platen, and a lever for actuating the pawl; said attachment comprising a bracket member secured to the frame of the carriage, an outstanding arm carried by the bracket, a lever pivotally supported on said arm, a link connected between said last-mentioned lever and said first-mentioned lever, pivotally mounted operator operated means for actuating said second mentioned lever, for actuating the pawl, and stop means for limiting the pivotal movement of said pivotally mounted actuating means to substantially ninety degrees, the link, said second mentioned lever, and said pivotally mounted actuating means being designed and proportioned to reduce the speed of the first mentioned lever, during the final increments of pivotal movement thereof, in response to substantially uniform speed of operation of the pivotally mounted actuating means.
5. In a typewriting machine including a shiftable carriage having a rotatable platen mounted thereon, pawl and ratchet mechanism for intermittently rotating the platen to effect line spacing, and means including an operator operated lever for driving the pawl and subsequently laterally shifting the carriage, the combination with said pawl and lever of motion modifying means interposed therebetween, said motion modifying means including a cam having a control contour of predetermined design and means for communicating the motion of the lever modified in accordance with the cam contour to the pawl whereby to rotate the platen without overrun, said motion modifying means also including means for subsequently shifting the carriage at full speed.
6. In a typewriting machine including a shiftable carriage, a platen rotatably mounted on the carriage, and pawl and ratchet mechanism for intermittently rotating the platen, the combination of an actuator member, motion transmission means operatively connecting the actuator member with said carriage and with said pawl for rotating the platen and then shifting the carriage when the actuator member is actuated, said motion transmission means including means for converting the movement of the actuator member into motion of non-uniform velocity of the pawl to rotate the platen without danger of overrun, said non-uniform velocity motion being characterized by an increment of relatively rapid movement of the pawl followed by an increment of relatively slow movement of the pawl whereby to rotate the platen quickly but without overrun, and means to shift the carriage at the speed of the actuator member.
7. In a typewriting machine a transversely movable carriage, a platen rotatably mounted thereon, a lever pivotally mounted on the carriage, pawl and ratchet mechanism actuated by the lever to rotate the platen, a cam member pivotally mounted on the carriage, said cam operatively engaging said lever, cam actuating means including an actuator member fixed with respect to the typewriting machine, connection means between said actuating member and said cam, means biasing the cam to a predetermined normal position and stop means limiting the extent of pivotal movement of the cam in response to operation of said actuating member whereby operation of the actuating member first causes rotation of the platen and then shifts said carriage upon engagement of the cam with said stop means.
8. In a pawl and ratchet mechanism a ratchet member mounted for rotation, a pawl for intermittently driving the ratchet member, means for movably mounting the pawl in operative relation

to the ratchet member, means for moving the pawl into and out of driving engagement with the ratchet member, said means including a link operatively connected to the pawl, means for oscillating the link and means for constraining the point of connection between the link and said link oscillating means to move in a path

substantially parallel to the path of movement of the pawl during the initial stages of movement of the pawl and to move transversely of the path of movement of the pawl during the final stages of movement thereof.

GARRED T. HARRIS.
